B.C. Bailey,

Double Acting Pump.

No. 103,960.

Patented June 7, 1870.

United States Patent Office.

BENNETT C. BAILEY, OF CONSTITUTION, OHIO.

Letters Patent No. 103,960, dated June 7, 1870.

IMPROVEMENT IN PUMPS.

The Schedule referred to in these Letters Patent and making part of the same

To all whom it may concern:

Be it known that I, BENNETT C. BAILEY, of Constitution, in the county of Washington and State of Ohio, have invented a new and useful Improvement in Pumps; and I do hereby declare that the following is a full, clear, and exact description of the same, reference being had to the annexed drawings, making part of this specification, in which—

Figure 1 is a perspective view;

Figure 2 is an elevation of one of the eccentrics and pump-rods; and

Figure 3 is a perspective view of the chamber, showing the interior construction in dotted lines.

The same letters are employed in all the figures in the indication of the same parts.

My improvement consists in the arrangement of a series of pump-cylinders in one case, said cylinders being connected by intermediate chambers formed in the case so that the water shall flow through the series, entering at the bottom of one cylinder and escaping from the top thereof into the next in the series, each cylinder having its own plunger.

The said plungers are operated by eccentrics placed on one driving-shaft, and are so set that they shall be in different parts of their strokes at the same time, so as to cause a continuous discharge of the water from the spout, and also to cause a uniform and continuous resistance in order to maintain the regular motion of the driving mechanism, and avoid the unequal resistance incident to pumps having a single plunger ejecting the water only as the plunger rises.

In the annexed drawings—

A is a metallic case, in which the pumps are all inclosed, the plungers playing vertically in a series of tubes, a , a' , a'' , and a''' .

The tube a is connected with the water in the well by a pipe opening into it at the bottom. These tubes are connected on the sides so as to form two compartments in the case, one on each side of the tubes.

Partitions are extended across one of the compartments from the tubes a' and a'' , to the case, so as to subdivide it into three separate compartments.

The water drawn into the tube a flows out through a hole in the top thereof into the compartment b . From the bottom of the latter it flows into the tube

a , and from the top thereof into the compartment b' , and thence successively through the intermediate similar parts to the tube a'' , from which it flows into the compartment on the opposite side of the tubes, and thence upward through the tube a''' , opening through the top of the case into the eduction-pipe.

Plungers C are placed in the several tubes having an ordinary valve, C' , rising to permit the water to pass through the plunger on the descending stroke, and closing on its seat with the ascending stroke.

These plungers are attached to the rods D , on the upper ends of which are the yokes D' , which inclose the circular cams E , eccentrically attached to the shaft F , which may be driven by any convenient power.

These eccentrics E are set at right angles to one another in continuous series, so that the first shall have risen one-half its stroke when the second one begins to rise, and so on, the third beginning to rise when the first begins to descend, so that the water raised by the first in the series shall be carried from one pump to another, and expelled in a continuous stream, the pumps offering a constant resistance to the power used to drive them, as two of the plungers will always be rising in different parts of their stroke while the other two are in like manner descending.

The rods D work through stuffing-boxes in the ordinary manner. No other valves are necessary than those in the plungers.

What I claim as my invention, and desire to secure by Letters Patent, is—

The arrangement, within a tight casing, subdivided into compartments, of a series of lifting-pumps, the plungers of which are set in such a manner that they shall be in different parts of their strokes at the same time, substantially as and for the purpose set forth.

In testimony whereof I have signed my name to this specification in the presence of two subscribing witnesses.

B. C. BAILEY.
